REMOTE CONTROL SYSTEM

George W. Baughman, Swissvale, and Norman F. Agnew, Penn Township, Allegheny County, Pa., assignors to The Union Switch & Signal Company, Swissvale, Pa., a corporation of Pennsylvania

Original application March 28, 1940, Serial No. 326,440, now Patent No. 2,303,875, dated December 1, 1942. Divided and this application August 21, 1942, Serial No. 455,578

10 Claims. (Cl. 177—353)

Our invention relates to remote control systems, and more particularly, to the communication or line circuits for centralized traffic control systems for railroads, in which a train dispatcher's office or other suitable point of control is connected with a plurality of field stations by line wires, over which impulse codes of signals are transmitted at times for controlling selected devices at the stations, and at other times for indicating the condition of station devices at the office.

Our invention is an improvement upon the system disclosed in Letters Patent of the United States No. 2,229,249, granted January 21, 1941, to L. V. Lewis, for Remote control systems. The present application is a division of our copending application, Serial No. 326,440, filed March 28, 1940, for Remote control systems, issued as Letters Patent of the United States No. 2,303,875, on December 1, 1942.

Since a dispatcher's telephone or telegraph line is generally required in connection with systems of this character, it is almost always the case that line wires are available throughout the length of any stretch of territory which is to be controlled by a centralized traffic control system, which are suitable for use for communication by code between the office and stations of that system, but which are already in use for other communication purposes.

One object of our invention is to provide an improved centralized traffic control system of the code type which is adapted to employ existing line wires for the transmission of code signals, without interference with the joint use of these wires for telephone and telegraph communication or for other purposes.

It is often convenient to employ the dispatcher's telephone line for C. T. C. communication. This generally comprises two line wires across which way station telephones and call selectors are bridged, and which, in addition, is "simplexed" to provide a continuous metallic circuit over the two line wires in multiple which may be included in a through duplex telegraph circuit. Furthermore, a "message" line which is similarly arranged generally parallels the dispatcher's line, in which case a long distance or phantom telephone circuit is usually superimposed upon the two telegraph branches, but as is well-known, this requires that a reasonably accurate balance be maintained between the two side circuits. On this account it is preferable to maintain the continuity of the line wires intact from end to end. This is accomplished

in the system of our invention by so arranging the C. T. C. apparatus that it may be connected to the line wires by means of simple bridged connections, and in our system there is no C. T. C. apparatus whatever in series with the line wires, an arrangement which is also of advantage in testing the line circuits and in arranging for the independent maintenance of the different services as usually provided.

10 The system of our invention as herein disclosed employs two non-interfering sources of current of different characters normally connected to the opposite ends of the line, the one at the office end being employed for the transmission of control codes to the several stations, and the one at the remote end being employed for the transmission of indication codes from the stations to the office. In respect to this feature, the present invention is an improvement upon that disclosed in the Letters Patent of the United States No. 2,224,374, granted December 10, 1940, to George W. Baughman, for Remote control systems.

Heretofore bridged line circuit systems have 25 usually required sources of line current at each field station, and consequently the series C. T. C. circuit as illustrated, for example, in Patent No. 2,229,249 above mentioned, has generally been preferred because it can be energized more conveniently and economically when the source of current is centrally located at a central office where it may be readily maintained by the usual supervisory forces in charge of the wire plant. These advantages are attained in the system 30 herein disclosed even though two sources of line current are used, inasmuch as one of these may be located at the C. T. C. office as heretofore, while the second may be located at another point where supervision is available, a suitable point being the main office at which the remote end of the line is terminated, even though this may be situated at a considerable distance beyond the last C. T. C. station.

Another object of our invention resides in the 45 provision of apparatus for signaling to a central office from a plurality of spaced points located along a line circuit by merely connecting the line wires together, preferably through an impedance suitably arranged so as to permit the joint use 50 of the line wires for other purposes without interference. Our invention also includes in a system of this character provision for signaling from the transmitting stations in the field not only in one direction to the control office but also in the opposite direction to lock out the apparatus at any

point more remote from the office which is attempting to gain control of the line at the time. With this arrangement the source of current for the code is always back of the transmitter, which, as is well-known, is advantageous from the line transmission standpoint, as it permits a much higher degree of attenuation of the line currents to be tolerated and permits simple one way repeaters of well-known forms to be interposed in the line as required, and is therefore well adapted to long distance transmission purposes.

Other objects, purposes and features of our invention will be pointed out as the description proceeds.

Two modifications of our invention will now be described, and the novel features thereof will then be pointed out in claims.

Referring to the accompanying drawings, Fig. 1 illustrates in diagrammatic form one form of centralized traffic control apparatus embodying our invention employing a source of direct current at the office and a source of alternating current at the remote end of the line for two-way code communication between a control office and a plurality of stations connected by line wires which are continuous from end to end. Fig. 2 illustrates the second form of our invention, in which alternating currents of different frequencies are used for code transmission in the two directions.

Similar reference characters refer to similar parts in each of the several views.

Referring to Fig. 1, the reference characters Y and Z designate the two line wires which provide a circuit for code communication between the office and stations of our centralized traffic control system, and it has been assumed that the line wires are arranged to provide other communication facilities in a manner which is more or less typical of actual conditions in this field, but with which we are not concerned further than to point out the variety of facilities that may be provided and to make clear that these facilities and our C. T. C. system are mutually noninterfering. These facilities will first be briefly explained.

Primarily, the line wires Y and Z provide a telephone circuit arranged for train dispatching purposes, and are connected at one end through condensers 2 and the telephone transformer 3 to telephone apparatus 5 located at the dispatcher's office, and at the other end through a similar connection to similar telephone apparatus 5 located at another main office. The dispatcher's office is also provided with a telephone call selector system which is assumed to be of the type shown in the Field Patent No. 1,343,256, granted June 15, 1920, comprising a plurality of code wheels 39 by which the dispatcher may transmit impulse codes to selectively call various way stations to establish telephone communication therewith. Since these stations are all alike, but one is shown, as indicated by the legend "Selector station" on the drawings, and each comprises a selector 72 bridged across the line wires Y and Z through a condenser 74, for selectively operating a call bell 76. The station operator, when called, establishes a connection with the dispatcher's office by connecting his telephone across the line by means of jack 77. In order to facilitate an understanding of this apparatus, the reference characters designating the elements of the selector system shown herein are the same as those of the Field patent.

The dispatcher's line is "simplex" in the

usual manner by the provision of a choke coil 1 and resistors 8 and 9 bridged across the line wires Y and Z at each end, to the mid point of which a connection is made to a wire X1 or X2, to provide a duplex telegraph circuit extending from ground at each end through standard terminal apparatus such as that shown connected to wire X1, comprising the line batteries B1 and N1, the contacts of the pole changer PC1, and thence differentially through the windings of the line relay R1 to wire X1 or X2, or through an artificial line AL to ground.

The dispatcher's line is also "phantomed" in a well-known manner, the two line wires Y and Z in multiple constituting one side of a telephone circuit extending from a telephone jack 6 at each end over wire U1 or U2 to a connection to the line wires Y and Z effected at the mid point of condensers 2. It is to be understood that the other side of the phantom circuit, not shown, is similarly arranged and comprises another pair of line wires, similar to Y and Z. It will be seen that each side of the phantom circuit, one of which comprises the line wires Y and Z in multiple, is employed jointly for telephone and telegraph purposes in accordance with a well-known composite arrangement, by reason of the condensers 2 in series with wires U1 and U2, and of the choke coils 10 in series with wires X1 and X2, and condensers 11 connected between these wires and ground.

The central office equipment of the C. T. C. system of our invention is assumed to be located at the dispatcher's office, this being identified by the legend "Office" in Fig. 1, and the C. T. C. field stations are assumed to be located at various points along the line indicated by branch connections to line wires Y and Z. Since all the C. T. C. stations are similarly arranged, for simplicity but one is shown, this being indicated by the legend "C. T. C. station" on the drawings.

The C. T. C. apparatus which is employed in the system of our invention for generating and receiving the codes may be of any suitable type, but in the specific embodiment of our invention disclosed herein this is to be understood to be of the well-known "time code" type as disclosed in the Lewis Patent No. 2,229,249 hereinbefore referred to, but modified in certain respects in accordance with the requirements of our invention as will hereinafter be pointed out. In the drawings of this patent, the relay contacts are identified by lower case letters, and to facilitate an understanding of our invention, we have designated those relay contacts shown in the accompanying drawings which correspond to contacts of correspondingly designated relays in the system of this Lewis patent by the same reference characters as are employed in the patent, while other contacts are identified by number. Furthermore, relays located at the office are distinguished by the prefix O, where similar relays are used at the office and stations, as in the patent, and it is to be understood that all of the C. T. C. apparatus the operation of which is not specifically described herein functions in the manner described in the patent. The circuits by which the slow acting relays L are controlled by the line relays as shown herein and likewise the circuits for the master relays OM and M are similar to the corresponding circuits of the patent and are reproduced herein merely for convenience.

Our invention relates particularly to the provision of improved line circuits and those dis-

closed herein differ very materially from that of the Lewis patent, where the office line relay OR and the station line relays R are all normally energized in series over line wires Y and Z by a central office battery 80. As disclosed herein in Fig. 1, the office battery 80 is employed as a source of code impulses for both the C. T. C. system and the selector system, in transmitting codes from the office, and the two systems are so arranged that but one can obtain control of the line at a time in a manner somewhat similar to that disclosed in Letters Patent of the United States No. 8,248,935, granted July 15, 1941, to George W. Baughman, for Remote control systems. In Fig. 1 the line wires Y and Z are normally energized by current from battery 80 over a connection which may be traced from line Y, through the upper coils of a low pass filter network 12 similar to that of the Field patent, back contact 13 of the connecting relay 86 of the selector system, back contact 14 of relay PC, back contact b of the C. T. C. transmitter relay OT, battery 80, back contacts 15 and 17 of relays PC and 86, the lower coils of the filter 12 to wire Z. Relay PC is an additional relay, not shown in the Lewis patent, the purpose of which will be explained hereinafter.

The station line relays R employed herein are of the high resistance biased polar type. In Fig. 1 each relay R is connected across the line wires Y and Z through a low pass filter 12, over back contacts 29 and 30 of the station master relay M, and is normally energized by current from the office battery 80 to maintain its left-hand or front contact 58 closed, as shown. Each relay R as employed herein therefore functions to control the station coding unit precisely like the normally energized relay R of the Lewis patent, in response to the control codes delivered to the line circuit as the result of the periodic opening of contact b of the office transmitter relay OT as described in that patent. For convenience, the normal direction of current in the winding of each biased polar line relay is indicated by an arrow.

The office line relay OR is also of the biased polar type like the relays R, but it is normally energized from a different source, namely, by amplified and rectified currents supplied over line wires Y and Z from a source of alternating current indicated by the supply terminals BX1 and CX1, which source is connected through a transformer 75 across the line wires at a point adjacent to or at the right of the last station connection, as shown.

In view of the fact that the line wires are arranged in Fig. 1 for joint communication purposes, a relatively high frequency of alternating current is employed to avoid telephone interference, but it will be understood that under other circumstances sixty cycle current or the like may be used. As shown, therefore, the terminals BX1 and CX1 represent a source of alternating current of a frequency f_1 above the voice frequency range which continuously supplies current to the line wires Y and Z through transformer 75 and a coil 78 and condensers C1 tuned to the frequency f_1 . This apparatus may be located at the main office at which the line wires Y and Z terminate, for convenience in maintenance, even though this may be at a considerable distance beyond the last C. T. C. station, as already mentioned. The alternating current received at the C. T. C. office over line wires Y and Z energizes a circuit tuned to the frequency f_1 comprising

the coil 81 and condensers C1 bridge across line wires Y and Z, the resonant potential across coil 81 being amplified in a conventional manner by the amplifier A if required. The output of amplifier A of frequency f_1 , passes through transformer 83 and is converted to direct current by rectifier 84 to energize the office line relay OR.

The starting circuit at the office by which relay OM is energized to initiate control codes is arranged as heretofore, to include a front contact c of a start relay identified by the legend "Start" on the drawings, and back contacts b of relays OL1 and OL2. Since the two last named relays are both released only when relay OR remains steadily energized, it will be apparent that control codes can be initiated as heretofore only when the system is in its normal at rest condition.

However, this difference is to be noted: Since the office line relay OR as shown herein is energized by a source at the distant end of the line, it follows that a control code, being dependent upon the operation of relay OR, cannot be delivered to an open line, nor can it be delivered to a short circuited line as when a series line circuit is used as in the system of the patent, but only to a line that is free and available throughout its entire length, and that either a cross or an open circuit in the line at any point is immediately made manifest at the office by the release of the line relay OR, so that the proper action may be promptly taken.

When relay OT operates its contact b to deliver a control code, relay OR is operated in unison with the station relays R by the contact 85 of relay OT just as if relay OR were in series with the battery line as in the system of the patent. Thus each time relay OT picks up to open the line circuit at its contact b, relay OR is deenergized by the opening of its local circuit at contact 85 of relay OT, causing relay OR to operate its contact 24 to the left to connect terminal B to wire 18, which corresponds with the wire leading to the back contact of the normally energized office line relay OR of the Lewis patent. Likewise, each time relay OT releases to close the line circuit, the local circuit for relay OR is completed at contact 85 to restore relay OR to its normal position as shown, thereby to connect terminal B over its right-hand contact 24 to wire 17, which corresponds with the wire leading to the front contact of relay OR of the patent. It will be clear that during the transmission of control codes, relay OR as disclosed herein functions to control the office coding unit in the same manner, and consequently these codes will be transmitted precisely as described in the patent.

The wires 17a and 18a leading to contact 58 of each station line relay R correspond to the control wires of the coding units which lead to the front and back contacts, respectively, of the station line relays R of the patent, and consequently the stations will receive the control codes as described in the patent. No further description of the transmission or reception of control codes is deemed necessary.

A feature of our invention is the transmission of indication codes by shunting the line, that is, by connecting the line wires together periodically over a contact of the station transmitter relay T to thereby divert the current supplied constantly to the line wires from the source at the distant end away from relay OR, so that relay OR will be released periodically to repro-

duce the code thus delivered to the line wires by relay OT . In Fig. 1 a high frequency bridge across the line, which presents a minimum impedance to the frequency f_1 delivered by the alternating current source having the terminals BX_1 and CX_1 , extends at each station from line wire Z , through one of the condensers C_1 and a coil 78 tuned to the frequency f_1 and over contacts 90 and 91 of relays E and T and the other condenser C_1 to line wire Y . A low frequency, or direct current bridge, which is closed at the same time, extends from line wire Z through the low pass filter 12 and over contacts b of relays E and T to line wire Y .

It will be seen that in response to the code operation of the station transmitter relay T , the effect of closing contact 91 is to shunt the current of frequency f_1 from the office line relay OR , and the effect of closing contact b of relay T is to shunt the current from battery 80 from the station line relay R , since this shunt is applied across the terminals of relay R , so that these relays release each time relay T picks up the same as when they are included in a series circuit including a back contact of relay T as in the patent. In addition, a second high frequency bridge is closed at the beginning of an indication code for the purpose of initiating the code, extending over front contact 92 of relay M and back contact 93 of relay LBP , and a second low frequency bridge is closed at the same time over front contact 30 of relay M and back contact 31 of relay LBP .

The transmission of an indication code by a C. T. C. field station will now be explained. It is to be understood that a change in condition of a station device having indications to transmit picks up a start relay ST , which in turn, provided the station line relay R is steadily energized, picks up the master relay M to prepare circuits for governing transmitter relay T , and that relay T picks up in response to the closing of contact e of relay M , in the usual manner. Relay T , when picked up, shunts line wires Y and Z by closing its contacts b at 91 as already explained. Relay M by the operation of its pole changer contacts 29 and 30 reverses the connections of relay R and at the same time completes the shunts including the front contacts 92 and 30 . It will be seen, therefore, that at the beginning of the code, the shunt is applied by relay M slightly before relay T picks up, and that relay R is released at about the same time that relay T picks up. The current in the portion of the line circuit extending to stations more remote from the office is reduced to release the line relays at these stations, while at the same time, the alternating current in the line portion extending to the office is reduced to release relay OR , as a result of connecting the line wires together at the transmitting station by relay M , but since the shunts are selective as to frequency the use of the line wires for the transmission of other frequencies, such as for voice frequency communication, is not interfered with.

Furthermore, when the line is shunted the current flow from battery 80 will be limited principally by the impedance of the intervening line wires, and the battery voltage as measured across line wires Y and Z will decrease in proportion to the distance from the office to the transmitting station to a value which is sufficiently low to reliably release the relay R at that station as well as those at most remote stations. It may be that this voltage is only slightly less than that

of battery 80 at points near the office, if the shunt is applied at a far distant point. Consequently the shunt cannot be relied upon for the release of the relays R at stations between the office and the transmitting station, when long distances are involved. Our invention includes provisions for releasing these relays positively, this being effected in Fig. 1 by a reversal of the line polarity, as will now be explained. When the office line relay releases in response to the closing of front contact 92 of relay M , it disconnects terminal B from wire 17 and connects it to wire 18 , so that the timing relays OL pick up sequentially, as described in the Lewis patent. Relay OR also completes a circuit from terminal B over wire 18 , back contact d of relay LBP and back contact 59 of relay OM through relay PC to terminal C . Relay PC therefore picks up and its contacts 14 and 15 reverse the polarity of the current delivered by battery 80 to the line wires Y and Z . When relay $OLBP$ picks up, a stick circuit for relay PC is completed from terminal B , contact 35 of relay $OLBP$, back contact 36 of relay $O16$, front contact 37 and winding of relay PC to terminal C . Relay PC remains energized until its stick circuit is opened either by the energization of relay $O16$ at the end of a completed code, or in other cases, such for example as when relay OR is accidentally reversed as a result of a line failure, by the release of relay $OLBP$.

The reversal of the line polarity by relay PC , which occurs at about the same time as the station relay T picks up, releases the line relays R at the remaining stations, or more particularly, at each station relatively so close to the office in comparison to the location of the transmitting station that the low frequency shunt across line wires Y and Z is not sufficient to effect the release of the corresponding line relay. At all stations, therefore, the line relays R will release at nearly the same time, due either to the shunt initially applied by relay M at the transmitting station or to the resulting reversal in the polarity of the line current, and each will disconnect terminal B from wire $17a$ and connect it to wire $18a$ to effect the sequential energization of the associated timing relays L . It will be seen that each relay R which is supplied with current of reverse polarity during the transmission of the code, that is, the relay R at each station that does not have its relay M picked up, will remain in its reversed position for the duration of the code to hold relay $L2$ energized over wire $18a$, so that its starting circuit will be held open at contact b of relay $L2$. The two shunts across the line wires Y and Z which are due to relay M are opened at contacts 31 and 93 , respectively, as soon as relay LBP picks up and are held open by relay LBP for the duration of the code. When relay LBP picks up, it causes relay T to release to complete the first step of the code, as explained in the Lewis patent, whereupon the two shunts across the line wires Y and Z which are due to relay T are opened at contacts b and 91 , allowing relay R at the transmitting station and the office line relay OR to pick up. Relay T then continues to operate its contacts repeatedly in the usual manner to transmit the code, relay R at the transmitting station and relay OR at the office picking up each time relay T releases, and releasing each time relay T picks up, to govern the operation of relay T and of the station coding unit precisely as heretofore, so that relay OR operates in unison with relay R and controls the office

coding unit in the usual manner to receive the code.

As explained in the Lewis patent, each indication code has sixteen steps, the last step comprising the return of the line circuit to its normal condition, a relay 16 at the transmitting station and a similar relay O16 at the office being picked up momentarily on this step. It will be evident that whereas in the system of the patent all line relays assume their normal position at the beginning of this step, in the present case that is true of the office line relay OR and relay R at the transmitting station only, the remaining line relays having been held reversed due to the reverse polarity of the line current.

At the office, relay O16 opens its contact 36 at the beginning of the final step, thereby opening the stick circuit for relay PC, which therefore releases to restore the line polarity to normal. At this time relay OR is energized and so remains picked up.

At the transmitting station, relay 16 at its contact 40 disconnects wire 18a from the right-hand contact 58 of relay R and connects wire 17a to that contact, and at its contact c opens the stick circuit for relay M thereby releasing relay M to restore the connections of relay R to normal at contacts 29 and 30 and to complete the restoration of the station coding apparatus to normal. It will be seen that relay R at the transmitting station will be reversed momentarily on the last step unless relays PC and M happen to release at precisely the same time, but that this is without effect because the temporary connection over front contact 40 of relay 16 maintains the coding unit in the same condition as if relay R remained steadily in its normal position.

The restoration of the line polarity to normal by relay PC causes the line relays R at the remaining stations to assume their normal positions, the resulting operations of restoring all the apparatus to normal then being effected in a well-known manner as explained fully in the patent.

It will be apparent that the mode of initiation of an indication code as above described is positive in its action to prevent interference in the event the office and a station initiate codes at the same time. More particularly, when relay T releases to begin the second step of an indication code, the associated relay R is held released on the first step unless current of reverse polarity is received from the office. If the office initiates a control code at this time, the line will be held open by relay OT for a relatively long interval to release relay L1 to thereby complete the usual pick-up circuit for relay E, which circuit as shown includes back contact g of relay L1, front contact c of the counting relay 1, contact 41 of relay LBP and the reverse contact 58 of the line relay R. Relay E upon picking up opens its back contacts b and 90 in the shunts including contacts b and 91, respectively, of relay T, and also opens the circuit for relay M at its contact d to release relay M to stop further transmission from the station. Relay M upon releasing conditions the station coding unit to receive the control code, by rendering relay R again responsive to line current of normal polarity.

It may happen, however, that two or more stations initiate indication codes at the same time. In this instance they may continue in operation as long as the code elements are alike,

but when a difference occurs one or another is locked out by means of an additional pick-up circuit provided for the station relay E.

It is to be understood in this connection that 5 as described in the Lewis patent, the code selection of the several stations and of the corresponding office panels is effected by the combination of three long and four short steps in a group comprising steps 2 to 8, inclusive, of each 10 code. The code calls are identified by the long steps which they contain, for example, when the second, third and fourth steps of a code are long and steps five to eight are short, the station employing the code is designated 234 and a selector 15 relay 234S at the office and a corresponding relay S at station 234 will be picked up.

It will be evident from Fig. 1 that when relay T picks up to begin an odd-numbered step of the code, the associated relay R will release, and 20 that if relay T remains picked up to produce a long step, the shunt produced by contact b of relay T at the transmitting station will remain effective at any station more remote from the office for a corresponding length of time. At any 25 such station having a code call in which the corresponding step is short, relays R and T will both be deenergized for a time equal to the difference between a short and a long step, during which time a lockout circuit will be closed from terminal B, right-hand contact 58 of relay R, front contacts 41 and 42 of relays LBP and M, back contact 43 of relay T, relay E to terminal C, so that relay E will pick up to establish a stick circuit at its contact a and to open its contact 30 d to release relay M and to also open its contacts b and 90 to prevent the transmission of any additional code elements from that station.

On the other hand, whenever relay T releases 35 to begin an even-numbered step of a code, it is necessary that relay R become energized immediately to open the lockout circuit for relay E just traced before relay E picks up, as ordinarily occurs because relay R is relatively quick acting in comparison with relay E. If, however, relay T 40 remain released to produce a long even-numbered step, a shunt applied by another station nearer the office having a call in which the corresponding even step is short will release relay R at the more remote station to pick up relay E over its lockout circuit. It will be seen therefore that a long odd-numbered step takes precedence over a short one, but that a short even-numbered step takes precedence over a long one. To insure that the shunts produced by relays T are fully effective, it is desirable to assign the code calls to the several stations in a geographical order, that is, so that the call for each station is superior to those for all more remote stations and inferior to those for all stations nearer the office. The most superior code call is 357, consequently, as indicated in Fig. 1, this is assigned to the station nearest the office, the next in the order of code superiority is the code call 358 which is assigned to the second station; next come 356, 378, 361, 368 and 345, in that order, and if all the codes are used, the most remote station will have the most inferior code call 246.

It will be apparent from the foregoing that when indication codes are initiated by two or more stations at the same time, the station nearest the office retains sole control of the line, and that several codes initiated simultaneously will be transmitted one at a time in a predetermined order, as heretofore.

The relation of the dispatcher's telephone call

selector apparatus to the C. T. C. system will now be explained. This apparatus, as explained in the Field patent, comprises a plurality of code wheels 89, one for each selector, of which but one is shown herein, each of which when wound up and released makes one revolution during which a connecting relay 86 is energized to connect a source of direct current to the line over the contacts 44 and 45 of a pole-changer relay 87. As the code wheel rotates, relay 87 is intermittently energized over a circuit including the code wheel contacts 96 and 97 in accordance with the arrangement of the code wheel teeth to deliver a code of impulses of alternately opposite polarity to the line wires Y and Z to operate the selectors 72.

As disclosed herein, the selector apparatus is arranged so that the operation of a code wheel is ineffective unless it is released when the C. T. C. apparatus is in its normal at rest condition as manifested by the deenergized condition of relay OLBP at the office. When relay OLBP is in its released position, the release of a code wheel completes a circuit from terminal B at the code wheel contact 96 over code wheel 89, back contact 46 of relay OLBP, relay 86 to terminal C. Relay 86 picks up to disconnect the C. T. C. line battery 80 from line wires Y and Z and to connect the line wires over its front contacts 13 and 17 to the pole changer contacts 44 and 45 of relay 87.

Since the selectors require a considerably higher voltage for their operation than the usual C. T. C. line relay, it is customary to provide a separate source of line current, which in practice usually comprises rectified alternating current obtained by means of a vacuum tube rectifier 47 and transformer 48 having its primary connected to the local alternating current lighting circuit as indicated by the legend "a. c." in Fig. 1, with a tank condenser 49 connected across the transformer secondary in series with the tube, as shown.

When relay 86 picks up it completes a stick circuit at its contact 50 which remains closed until the code wheel returns to normal, and at contact 51 completes a circuit for energizing the filament of the rectifier tube 47. Tube 47 is to be understood to be of a type requiring its filament circuit to be closed for at least one-half second before sufficient electron emission is developed to deliver appreciable current to the line. Since relay 86 disconnects battery 80 from the line at the beginning of this period, each selector code begins with a long "line-open" period, similar to that of the first step of a C. T. C. control code, and which is likewise effective to lock out any field station that happens to initiate a code at that time. Relay 86 when energized opens the circuit for relay OR at contact 88, thereby holding relay OR reversed for the duration of the selector code, with the result that relay OL2 is energized to hold the pick-up circuit for relay OM open to prevent the initiation of a C. T. C. control code until the selector code is completed. When relay 86 releases at the end of the selector code, the closing of its back contacts completes the circuit for relay OR and reconnects battery 80 to the line to thereby restore the C. T. C. apparatus to its normal condition.

The selector codes and C. T. C. battery codes are mutually non-interfering in respect to the operation of the code receiving apparatus because of the difference in the relative proportion of long and short code elements as explained

more fully in Patent No. 2,259,573, granted October 21, 1941, to L. V. Lewis, for Remote control systems, and since the transmitters do not interfere one with another, for the reasons that have just been pointed out, and since the usual selectors have far too high a reactance to respond to the alternating current codes or to appreciably shunt the voice frequency currents, it will be clear that both systems may employ the same line channel without interfering with each other or with the joint use of the line wires as hereinbefore described.

A characteristic of the novel mode of transmitting indications from the field stations by connecting the line wires together as disclosed herein, is that the indication codes are transmitted in two directions at the same time in response to the operation of the contacts of the station transmitter relay T, for two different purposes. When relay T is operated to transmit an indication code, its contact 91 is effective to transmit an alternating current code in the direction from right to left, to which the office line relay OR responds, while at the same time, its contact b transmits a battery code in the opposite direction which as heretofore not only operates relay R at the transmitting station to govern the transmission but is also effective to lock out any station more remote from the office which initiates an indication code at the same time.

It is also to be noted that the disagreement between the positions of the relays T at two stations which locks out the station more remote from the office does not interfere with the alternating current code element then being transmitted to the office by the nearer station.

In this connection, it has already been explained that in respect to the odd-numbered code steps, a long step takes precedence over a short step. Thus if relay T at the transmitting station nearer the office remains picked up to maintain its shunt for a relatively long period, relay OR will be released for a corresponding long period irrespective of the release of relays T and M to remove the shunt at the more remote station. Furthermore, in respect to the even-numbered code steps, a short step takes precedence over a long step. Therefore if a relay T picks up to shunt the line after a relatively short interval, relay OR will release irrespective of whether or not the line is shunted at the same time by relay T at any station more remote from the office.

The apparatus of our invention may also be arranged to employ alternating current transmission in both directions. One manner in which this may be accomplished is shown in Fig. 2 which illustrates a modification of our invention which differs from Fig. 1 principally in that the office pole changer relay PC has been replaced by a frequency changer relay FC, and in place of battery 80, two sources of alternating current of frequencies f_2 and f_3 , respectively, are provided at the office, of which only the terminals are shown, these being designated BX2 and CX2 for the source of frequency f_2 , and BX3 and CX3 for the source of frequency f_3 . Current of frequency f_1 is supplied to the remote end of the line from a source having the terminals BX1 and CX1 in the same manner as in Fig. 1, and each station line relay R in Fig. 2 is arranged to respond normally to current of frequency f_2 only, in the line wires, but responds

to current of frequency f_3 only, in the event the associated relay M is picked up. In other words, alternating current of frequencies f_2 and f_3 in the line circuit of Fig. 2 takes the place of direct current of normal and reverse polarity, respectively, in the line circuit of Fig. 1.

Referring to Fig. 2, a local circuit is normally closed at the office extending from one terminal BX2 of the source of frequency f_2 over back contacts b and 94 of relays OT and FC, condenser C2, the primary winding of a hybrid transformer 100, back contact 95 of relay FC to the other terminal CX2 of said source. The output of the hybrid transformer 100 is delivered by its secondary windings in one direction through a high pass filter indicated by the condensers 98 to the line wires Y and Z, and in the other direction to a balancing network 99.

Current received at the office from the source of frequency f_1 , which is connected across line wires Y and Z at the remote end of the line as already explained in connection with Fig. 1, passes through condensers 98 and the upper secondary windings of transformer 100 and thence through parallel resonant circuit elements designated f_2 and f_3 (to indicate that they are for blocking the passage of currents of the corresponding frequencies) and thence as in Fig. 1, through a coil 81 and condenser C1 tuned to the frequency f_1 , amplifier A, transformer 83 and rectifier 84 over back contact 85 of relay OT to relay OR.

Since the system of Fig. 2 does not use battery current in the line, no provisions other than selective tuning are needed to prevent interference with the telephone call selector system and the latter therefore does not need to be interlocked with the C. T. C. system as in Fig. 1 and accordingly is not shown in Fig. 2.

At each field station in Fig. 2 the line relay R is associated with the line by means of circuits which are generally similar to those provided for relay OR, but which differ by including a coil 81 and condenser C2 tuned to series resonance to render relay R normally responsive to current of frequency f_2 only, and by including parallel resonant elements comprising a coil and condenser designated f_1 to render relay R non-responsive to current of frequency f_1 , as shown. In Fig. 2, therefore, each station line relay R is normally energized by rectified alternating current supplied from the source of frequency f_2 at the office, while the office line relay OR is normally energized by rectified alternating current supplied from the source of frequency f_1 at the remote end of the line.

In the system of Fig. 2, relay OT is arranged to interrupt the current of frequency f_2 at its contact b to control the relays R, and to interrupt the local circuit for relay OR at its contact 85, to thereby effect the transmission of control codes to the stations in an obvious manner, relays OR and R operating in unison as in the other form of our invention.

With the apparatus of Fig. 2 in its normal condition, as shown, if relay M at a station picks up to initiate an indication code, the currents of both frequencies in line wires Y and Z are shunted, first over contacts 30 and 31 of relays M and LBP, and then over contacts b of relays E and T, as in the first form of our invention already described, thereby releasing relay R at the transmitting station and at each station more remote from the office, and also releasing the office line relay OR. Relay M at the transmit-

ting station furthermore at its contact 101 connects a condenser C3 in parallel with condenser C2 to change the tuning of the series resonant circuit governing relay R, so that upon removal of the shunt by the opening of contact 31 when relay LBP picks up, relay R will be responsive only to current of frequency f_3 . Relay OR upon releasing effects the energization of relay FC, over a circuit extending from terminal B, left-hand contact 24 of relay OR, wire 18, contact d of relay OLEP, contact 59 of relay OM, relay FC to terminal C, and relay FC picks up, completing its stick circuit at contact 103, and at its front contacts 94 and 95 relay FC connects terminals BX3 and CX3 of the source of frequency f_3 to the primary of transformer 100, disconnecting the terminals BX2 and CX2, and at the same time closes contact 102 to connect a condenser C3 in parallel with condenser C2 at the office to change the tuning of the primary of the transformer 100 to render it responsive to frequency f_3 . The change in frequency of the current delivered to the line at the office effects the release of each line relay R which is energized when relay FC picks up, and all the relays R will remain released for the duration of the code except the one at the transmitting station, as heretofore.

It will be seen, therefore, that in Fig. 2 the shunting of the line wires by relay T is effective to transmit an indication code of periodically interrupted alternating current of frequency f_1 from right to left to govern relay OR at the office, and to transmit a similar code of frequency f_3 from left to right for governing relay R at the transmitting station and for locking out any station more remote from the office which may happen to initiate an indication code at the same time, while the absence of current of frequency f_2 in the line insures that no station at the left of the transmitting station which is relatively so near the office that the shunting of the line at the transmitting station is ineffective, will initiate a code. It follows therefore that the coding units when controlled by the apparatus of Fig. 2 will function in the same manner as when controlled by that of Fig. 1, and it is believed therefore, that the operation of the system of Fig. 2 will be readily understood without further description.

Since in both Figs. 1 and 2 the currents employed for transmission in the two directions are of dissimilar character, the transmission distance may be extended by the use of ordinary one-way repeaters, and it follows therefore that not only may a wide variety of existing line facilities be made use of to provide the necessary transmission channels between the control office and the C. T. C. field stations, but the office may be located at any required distance without impairing the quality of the code transmission.

This may be readily shown by considering the initiation of indication codes as hereinbefore described. In the system of Patent No. 2,229,249 as used commercially, the length of the first step of an indication code although nominally a short step is considerably longer than the other short steps because of the additional relay operations occurring on that step, and in practice, relay T when first energized remains picked up for about 0.2 second. If the apparatus of Fig. 2, for example, is used with that system on a long line including repeaters, it will be apparent that when relay T first picks up, an impulse representing the effect of shunting the current of frequency

f1 at the transmitting station is propagated along the line through the repeaters to the office, to operate relays OR or FC successively, and then an impulse of current of frequency *f3* is propagated from the office back to the station to render current of that frequency available to pick up relay R upon the release of relay T. Obviously the length of the first step is not affected unless it is less than the time required for these impulses to travel twice the length of the line as described, which time, under any condition likely to be encountered in practice, is less than 0.2 second. Furthermore, the latter value, being arbitrary, may readily be increased to match the line conditions if required. Since except for the first step of an indication code as pointed out above, the system employs "one way" transmission with the source of the line signals back of the transmitter, the propagation time of the impulses due to long line conditions is of no practical consequence.

It is also to be noted that the C. T. C. apparatus of Fig. 2, since it is connected to the line wires through condensers of relatively small capacity, may employ line circuits which are quite different from those of Fig. 1, such for example, as an alternating current power transmission line.

Such a transmission line is almost always available throughout the length of territory comprising a C. T. C. installation. Usually the track switches, signals and other apparatus involved are energized locally by storage batteries maintained energized by the trickle-charge method, by energy supplied from an alternating current source over a transmission line comprising a pair of added line wires on the pole line carrying the communication circuits, the voltage in the power line being limited by practical considerations to the maximum value permissible in such circuits, that is, to less than 500 volts.

The system of Fig. 2 may be superimposed on such a line, as is self evident, but the system of Fig. 1 may also be used by the provision of suitable arrangements for preventing interference, such, for example, as those shown in Figs. 6, and 7 of our prior application, Serial No. 326,440.

Although we have herein shown and described but two forms of our invention, it will be understood that various changes and modifications may be made therein within the scope of the appended claims without departing from the spirit and scope of our invention.

Having thus described our invention, what we claim is:

1. In a remote control system, an office and a plurality of stations connected by two line wires, a line relay included in a branch circuit bridged across the line wires at each station, a normally closed code signaling channel including a first source of current and a transmitting contact located at the office, said channel also including said line wires and said line relays, means at the office for periodically operating said transmitting contact to control said line relays in accordance with different codes, a second normally closed code signaling channel including a line relay at the office, said line wires and a second source of current of different character from said first source connected across said line wires at a distant point, a code transmitter at each station effective when operated to connect said line wires together periodically in accordance with a code to shunt said first source to thereby control the line relay at such station and the line relays at

stations more remote from the office, each such operation being also effective to shunt said second source to control said office line relay, a code receiver controlled by said office line relay, and

5 means controlled by each station line relay for governing the operation of the associated code transmitter.

2. In a remote control system, two line wires extending from a control office through a plurality of stations to a distant point, a source of direct current connected across said line wires at said office, a source of alternating current connected across said line wires at said distant point, a direct current line relay connected across said line wires at each station, a normally energized line relay at the office responsive to alternating current only in said line wires, a code transmitter at the office effective to periodically disconnect said direct current source from the line wires to operate the station line relays in accordance with different codes, a code transmitter at each station effective to periodically connect the line wires together to shunt said alternating current to operate said office line relay in accordance with a code, and code responsive means controlled by each said line relay.

3. In a remote control system, two line wires extending from a control office through a plurality of stations to a distant point, a source of direct current connected across said line wires at said office, a source of alternating current connected across said line wires at said distant point, a direct current line relay connected across said line wires at each station, a normally energized line relay at the office responsive to alternating current only in said line wires, a code transmitter at the office effective to periodically disconnect said direct current source and said office line relay simultaneously from the line wires to operate the office and station line relays in accordance with different codes, means controlled by the office line relay and dependent upon its energization at least intermittently by the alternating current supplied from the source at said distant point for maintaining said code transmitter in operation to complete the transmission of said code, and means controlled by the station line relays selectively responsive to said codes.

4. In a remote control system, a line circuit extending from a control office through a plurality of stations to a distant point comprising two line wires, two non-interfering current sources connected across said line wires, one at the office and the other at said distant point, a line relay responsive to current from the office source only connected across said line wires at each station, a line relay responsive to current from the source at the distant point only connected across said line wires at the office, a code transmitter at the office effective to periodically disconnect the office source from the line wires to operate the station line relays in accordance with different codes, and a code transmitter at each station effective to periodically connect the line wires together to shunt the current from the source at the distant point to operate the office line relay in accordance with a code.

5. In a remote control system, two line wires extending from a control office to a distant point, a source of alternating current of one frequency connected across said line wires at said distant point, a source of alternating current of another frequency connected across said line wires at said office, a line relay at each station controlled over a branch circuit bridged across said line wires

and responsive to alternating current of said another frequency only, a code transmitter at said office effective to periodically disconnect said office source from the line wires to operate the station line relays in accordance with different codes, a normally energized line relay at the office responsive only to current of the frequency of the source at said distant point, code transmitting means at each station effective when initiated to change the connections of the associated line relay to render such relay responsive only to a third frequency, and to momentarily connect the line wires together to release the office line relay, means controlled by the office line relay when so released for supplying alternating current of said third frequency only to said line wires, and means controlled by the station line relay responding to said third frequency for continuing the operation of the associated transmitter to transmit a code to which the office line relay responds.

6. In a remote control system, a line circuit extending from a control office through a plurality of stations to a distant point comprising two line wires which are continuous from end to end to form a portion of a transmission circuit connecting said office and distant point, two non-interfering current sources for supplying current to which said transmission circuit is non-responsive connected to said line wires, one being located at the office and the other at said distant point, a line relay selectively responsive to current from the office source connected to said line wires at each station, a line relay at the office selectively responsive to the current from the source at said distant point and adapted to be controlled over said line wires, a code transmitter at each station effective when initiated to connect the line wires together periodically in accordance with a code to selectively shunt the line current supplied from the office to operate the line relay at such station, each such operation being also effective to selectively shunt the current supplied from said distant point to operate the office line relay but without varying the condition of said transmission circuit, and means controlled by each line relay for governing the operation of the associated code transmitter.

7. In a remote control system, line wires extending from a control office through a plurality of stations to a distant point, two sources of line current of different character located respectively at the office and the distant point, the one at the distant point being normally connected across said line wires, a line relay at the office selectively responsive to current from the source at said distant point, a line relay at each station selectively responsive to current from the source at the office, a code transmitter at each station effective when initiated to connect the line wires together periodically to produce a multiple impulse code of line current variations therein, means controlled by the office line relay for connecting the office source to the line wires for the duration of such code, means controlled by each station line relay for preventing the initiation of the associated transmitter when current from the office source is being supplied to said line wires, and means effective to stop the operation of any code transmitter which has started to deliver its code if such code is changed in character as manifested by the operation of the associated line relay, due to the operation of another code transmitter.

8. In a remote control system, a line circuit

- extending from a control office through a plurality of stations to a distant point, a line relay at the office and at each station bridged across said line wires, a normally closed signaling channel including said office line relay and said line wires, said channel having a source of current to which the station line relays are non-responsive connected to the line wires at said distant point, a transmitter relay and a master relay at each station, means controlled by each master relay when operated to initiate the operation of the associated transmitter relay, means controlled by each transmitter relay when operated for connecting the line wires together periodically to deliver a multiple impulse code to said line wires to control the office line relay, means controlled by the office line relay in response to the first impulse of such code for opening said second channel and for supplying current of a different character to the line wires to which none of the line relays are normally responsive, for the duration of such code, means controlled by each master relay when operated for conditioning the associated line relay to respond to said current of different character, and means controlled by the line relay at each station dependent upon its operation in accordance with a code identifying that station for continuing the operation of the associated transmitter relay to complete such code.
9. In a remote control system, a line circuit extending from a control office through a plurality of stations to a distant point, a line relay at the office and at each station bridged across said line wires, a normally closed signaling channel including said office line relay and said line wires, said channel having a source of current to which the station line relays are non-responsive connected to the line wires at said distant point, a transmitter relay and a master relay at each station, means controlled by each master relay when operated for conditioning the associated line relay to respond to said current of different character, means controlled by each station line relay for preventing the operation of the associated master relay to initiate a code during the time said current of different character is being supplied to the line circuit, and means controlled by the line relay at each station dependent upon its operation in accordance with a code identifying that station for continuing the operation of the associated transmitter relay to complete such code.
10. In a remote control system, a line circuit extending from a control office through a plurality of stations to a distant point, a line relay at the office and at each station bridged across said line wires, a normally closed signaling channel including said office line relay and said line wires, said channel having a source of current to which the station line relays are non-responsive connected to the line wires at said distant point, a transmitter relay and a master relay at each station, means controlled by each master relay when operated to initiate the operation of the associated transmitter relay, means controlled by each transmitter relay when operated for connecting the line wires together periodically to deliver a multiple impulse code to said line wires to control the office line relay, means controlled by the office line relay in response to the first impulse of such code for opening said second channel and for supplying current of a different character to the line wires to which none of the line relays are normally responsive, for the duration of such code, means controlled by each master relay when operated for conditioning the associated line relay to respond to said current of different character, and means controlled by the line relay at each station dependent upon its operation in accordance with a code identifying that station for continuing the operation of the associated transmitter relay to complete such code.
11. In a remote control system, an office and a plurality of stations connected by line wires extending from the office to a distant point, a line relay responsive only to direct current bridged across the line wires at each station, a line relay

bridged across the line wires at the office through circuit elements rendering such relay responsive only to alternating current, two normally closed signaling channels both including said line wires, one including a source of direct current at the office and the station line relays, the other including a source of current at said distant point and the office line relay, a code transmitter at each station effective when operated to connect the line wires together periodically through a 10

5 low pass filter to control the associated line relay and through a high pass filter to control the office line relay in accordance with a code, a code receiver at the office governed by the office line relay, and means controlled by each station line relay for governing the operation of the associated code transmitter.

GEORGE W. BAUGHMAN.
